UNITED STATES PATENT OFFICE

ALICE McL. JONES, OF NEW YORK, N. Y., ASSIGNOR TO PINAUD, INC., OF NEW YORK, N. Y., A CORPORATION OF NEW YORK

DESIGN FOR A VANITY CASE

Application filed March 5, 1931. Serial No. 38,948. Term of patent 14 years.

To all whom it may concern:

Be it known that I, ALICE McL. JONES, a citizen of the United States, and resident of New York city, county of New York, State of New York, have invented a new, original, and ornamental Design for Vanity Case, of which the following is a specification, reference being had to the accompanying drawings, forming a part thereof.

Fig. 1 is a perspective showing the top, side and end of a vanity case embodying my invention.

Fig. 2 is another perspective showing a side, end, and bottom of the same.

I claim:

The ornamental design for a vanity case substantially as shown.

ALICE McL. JONES.
